UNITED STATES PATENT OFFICE.

FRANZ HUNZIKER, OF LUCERNE, SWITZERLAND.

BRAKE.

Original application filed August 29, 1921, Serial No. 496,389, and in Switzerland June 23, 1917. Divided and this application filed September 23, 1925. Serial No. 58,171.

The present invention relates to improvements in brakes which operate on the rail by the friction of their surface on each side of the rail and which brake is attached to the vehicle in such a manner that it is able to move freely, as far as is necessary, transversely, and also as a whole or in parts to turn vertically to the plane of the track so that the contact surfaces of the brake can freely and without any interference lay themselves against the friction surfaces of the rails. The invention more particularly relates to brakes as described in the application, Serial No. 496,389.

15 The present application is a division of said co-pending application for Letters Patent Serial Number 496,389 filed August 29, 1921.

According to the present invention the 20 brake-arms are each provided with a movable brake wedge, moreover means are provided to move said wedges in or out of their working position. These wedges allow a very rapid and efficient action.

25 In the drawings some devices are shown diagrammatically by way of examples.

Fig. 1 illustrates the front view of the rapid-clutch brake.

Fig. 2 shows its side view.

30 Fig. 3 illustrates the view from above with parts in section.

Fig. 4 is the horizontal section on line A—B of Fig. 2 through the proper brake-parts.

35 Fig. 5 shows the top of a car of a lift with the brake.

Fig. 6 is a section on line C—D of Fig. 5.

Fig. 7 is a vertical sectional view of a modified form of the invention.

40 Fig. 8 is a horizontal sectional view of same.

In the construction shown in Figs. 1 to 4 two brake-wedges 31 with sliding-plates 22 are placed at the lower end of two brake-arms 33 at each side of the rail. The brake arms 33 are mounted in the frame 45 of the car in such a manner that they move freely transversely and, as a whole or in parts, turn vertically to the plane of the track as described more fully in the co-pending specification. The brake wedges are free to slide in the direction of the rails, and they are actuated by the double-armed lever 34 with joint-pins 35, pin 36, throw-out-rods 37 and locking spring 38. The brake-arms 33 are

held together above the rail by a connecting pin 39 with two strong brake-springs 40. A distance-ring 41 of said pin 39 ensures the proper distance between the two brake-arms when the brake is open, whereas a fish-plate 42 connects the upper ends of the brake-arms 33 at their proper distance. This fish-plate 42 with the brake-arms 33 is transversely movable on a girder 43 of the vehicle frame 45. The lower part of the brake is also movably held in a fish-plate 46 of the vehicle-frame. Two springs 47 maintain the open brake in its mean position whereas at the lower end it is guided along the rail. The two brake-arms 33 support themselves, together or singly turnable vertically to the track-plane, at one side against brake-shields 49 of the vehicle. Laths 32 at each side reach underneath the rail head and the nuts 21 prevent the vehicle from leaving the rails when the brake is being applied. The joints 35 allow the brake free movement as against its rods 34 to 37.

This brake operates in the following manner:

When the brake is open the locking-spring 38 resting against the vehicle-frame 45, is in tension and the rods 37 are kept in position by a throw-out device not shown in the drawing. When actuating the rods 37 the two brake wedges 31 are first of all thrown suddenly and forcibly in between the brake-arms by the force of the locking springs 38, until they rest against the rail-head freely and perfectly at each side, owing to the fact that the brake arms have their upper ends mounted for movement transversely of the frame and also mounted for horizontal pivotal movement, whether the vehicle is on the straight track or on a bend. The vehicle continuing on the move now draws the brake-arms 33 over the two wedges 31 resting on the rail until the arms 33 forced apart by springs meet the prominences 22 of the wedge 31 carrying the latter along. The 100 brake is now closed and it gradually brings the vehicle to a standstill owing to the sliding friction on the rail. The efficiency of the brake and the length of the run with the brake applied can be regulated by the more or less strong tension given to the brake-springs 40.

The efficiency of the brake is quite independent of the gradient, of the load carried and of the impulses of adhesion. For this 110

reason it can be applied to lifts just as well. It is a fact that the work of the catch brake-device attached rigidly to the lifts heretofore used, is affected unfavourably if 5 the lift for example is loaded unevenly, thus pressing the catch-brake-device to one side. A fall-brake freely movable attached to a lift will lead here also to increased safety, and to more rapid and more even 10 effect, and promote a more perfect pressure on the friction surface against the guide-rail, which will be of great advantage, especially with the heavy mining-hoists. It is not necessary that the guide-rail should 15 be a rail-road rail with vertical lifts, it may be smooth and without a head, as has been the usual practice. In Figs. 5 and 6 one mode of constructing the brake in connection with lifts is shown.

20 On the frame 50 of an elevator car, etc., two horizontal bars 51 are movably mounted in horizontal direction, extending above or below the car or lift from one rail 52 to the other. They are fitted at each side with 25 two brake-pieces 53 and they are interconnected by connecting-pins 54 and pressed against each other by springs 55 all made in such a manner that the bars attached to the lift are moving horizontally and freely 30 within certain limits. Two pairs of brake-wedges 56 are provided, the wedges resting on two double armed levers 57 hinged to a common vertical rod 58 fixed to a hoisting rope 59. A spring 60 abutting on a bearing 35 of the car at the one end and on the rod 58 on the other end pushes the wedges 56 between the pieces 53 as soon as the rope 59 breaks, or if the car lowers swiftly with an excessive speed, etc. The mechanism between the brake and the rope suspension can 40 be constructed otherwise as shown, but always in such a manner, that each brake shoe can adjust itself freely in any direction independently of the others even after 45 some wear, etc.

50 In any of the constructions shown, the brake pieces co-operating with the rails may be made adjustable in a direction perpendicular to the running face of the rails. 55 If for instance in the construction shown in Figs. 5, 6 the distance between two rails varies the brake pieces need have some play to adjust themselves with reference to each other. Care is to be taken that in any position each brake piece bears with its whole 60 braking surface on the rail co-operating therewith and that the distance between the co-operating friction faces is a minimum to ensure a rapid closing of the brake.

65 In the brakes used in connection with rail carriages a brake piece bearing on the upper horizontal face may be used provided provision for adjustment in vertical direction is made to eliminate the effect of wear, of lowering of the axles of the vehicle, and so on.

A brake constructed according to this principle is shown in Figs. 7 and 8. On each end of a beam 63 of the cage, car, etc. a guide piece 64 is attached embracing the rail 65. Two levers 66, 67 are arranged in 70 said guide piece pivoted on a bolt 68 passing through an elongated slot 69 of the web of the beam 63. The bolt 68 slides freely in said slot in such a manner that the free ends of the levers 66, 67 can follow the inequalities, the bends, etc. of the rail 65. Near the free ends of the levers 66, 67 they are traversed by a spindle 70 having a nut at each end and springs 71 between the nuts and the levers to press the levers 66, 67 against each other and on an abutment 75 66^a of piece 64 of such a manner that they do not touch the rail 65. Each lever 66, 67 has near its free end a slot 67^a running 80 in the direction of the rail 65. In each slot 85 a wedge 77 is slidably mounted resting on an arm 73 of a double armed lever pivoted on the beam 63 and actuated by some brake-gear which gear may be of any suitable construction. It is apparent that the braking surfaces of the levers 66, 67 follow closely 90 the co-operating faces of the rail 65; the co-operating faces are near each other and a rapid gripping and a self-adjustment of 95 the faces is attained.

I wish it clearly understood that various changes may be made without departing from the spirit of my invention, the principle as shown applied to lever-brakes may be applied to other brakes as well for instance to brakes having cams or some other 100 braking organ. The essential feature is that the braking element co-operating with the rail has sufficient freedom to adjust itself to the deviations of the rail.

Having now described my invention what I claim by U. S. Letters Patent is:—

1. A brake comprising in combination with a rail, self-adjusting gripping arms mounted in the frame of the carriage for universal angular movement so that it follows each deviation of the rail in any direction, wedges 110 slidably mounted in said arm, means to operate said wedges.

2. A brake comprising in combination with a rail two pivoted gripping arms, opposed to each other, adapted to be pressed against the rail, means to mount said arms on the vehicle for universal angular movement, in such a manner that the brake surfaces can unobstructedly adjust themselves to the inequalities to the lateral deviations and to the change of direction of the rail, wedges slidably in the direction of the rails 120 and mounted in close proximity to said rails, means to actuate said wedges.

3. A rail-brake comprising in combination with a rail, two pivoted gripping arms opposed to each other, adapted to be pressed against the rail, means to connect the said 130

arms with the vehicle for universal angular movement so that the brake surfaces thereof can adjust themselves unobstructedly transversely to the longitudinal axis of the vehicle and according to the position of the rail, wedges slidably mounted in said arms and co-operating with the rail, means to operate said wedges in said arms, means to removably connect the wedges to said arms substantially as described.

4. A rail brake comprising in combination with a rail two pivoted gripping arms adapt-

ed to be pressed against the rail, operating means for said arms and to which said arms are connected for universal angular movement so that said arms can adjust themselves unobstructedly to the changing direction of the brake rail, wedges slidably mounted in said arms and co-operating with the rail, means to move said wedges in guides of said arms, said means comprising a spring.

In witness whereof I affix my signature.

FRANZ HUNZIKER.
